D6-216. OR D 17160 EX

DESIGN FOR A RUG.

Design No. 17,160, dated March 1, 1887.

UNITED STATES PATENT OFFICE.

JULIUS PEGEL, OF CAMDEN, NEW JERSEY, ASSIGNOR TO JOHN BROMLEY & SONS, OF PHILADELPHIA, PENNSYLVANIA.

DESIGN FOR A RUG.

SPECIFICATION forming part of Design No. 17,160, dated March 1, 1887.

Application filed January 5, 1887. Serial No. 223,492. Term of patent 3½ years.

To all whom it may concern:

Be it known that I, JULIUS PEGEL, a subject of the Emperor of Germany, residing at Camden, in the county of Camden and State of New Jersey, have invented and produced a new and original Design for a Rug; and I do hereby declare that the photographic print accompanying this specification conveys to any one skilled in the art a clear understanding of the same, and is sufficient to enable such person to use my invention.

The leading features of my design consist of a center panel upon which is represented a mass of flowers and variegated colored leaves as springing or rising from the base of the panel. At each end of the design or rug is represented a floral scroll. The whole is represented as surrounded by a narrow border, A. At top and bottom is an ornamental border, B. The center panel is surrounded by a narrow border, C.

The photographic print shows only three-fourths of the design or rug. The right-hand end, or the part not shown, is exactly like the left-hand end, that is shown.

What I claim as my invention is—

The design for a rug, consisting of a center panel upon which is represented a mass of flowers and variegated colored leaves as springing or rising from the base of the panel, 30 and at each end of the design or rug is represented a floral scroll, the whole surrounded by a narrow border, A, at top and bottom an ornamental border, B, and the center panel surrounded by a narrow border, C, as shown.

JULIUS PEGEL.
